Des. 197,962
Patented Apr. 14, 1964

197,962

RESTAURANT BUILDING OR THE LIKE

Oscar F. Stone, 9048 Alcott St., Los Angeles 35, Calif.,
and Cecil E. Child, Venice, Calif.; said Child assignor to said Stone

Filed May 16, 1962, Ser. No. 70,168

Term of patent 7 years

(Cl. D13—1)

FIG. 1 is a perspective view of a restaurant building embodying our design.

FIG. 2 is a side elevational view thereof;

FIG. 3 is a front elevational view thereof; and

FIG. 4 is a reduced top plan view thereof.

The dominant features reside in the portions shown in full lines.

We claim:

The ornamental design for a restaurant building or the like, substantially as shown and described.
